United States Patent Office.

CHRISTOPHER G. CROSS, OF CHICAGO, ILLINOIS.

Letters Patent No. 80,533, dated August 4, 1868.

IMPROVEMENT IN GOVERNORS FOR STEAM-ENGINES.

The Schedule referred to in these Letters Patent and making part of the same.

TO ALL WHOM IT MAY CONCERN:

Be it known that I, CHRISTOPHER G. CROSS, of the city of Chicago, in the county of Cook, and State of Illinois, have invented certain new and useful Improvements in Governors for Steam-Engines; and I do hereby declare that the following is a full, clear, and exact description of the same, reference being had to the accompanying drawings, making a part of this specification, in which—

Figure 1 represents a vertical cross-section.

Figure 2, a top sectional and bottom view of the lower valve.

Figure 3, a top, side, and bottom view of the upper valve.

Figure 4, a back view, and

Figure 5 a front view, with a portion of the casing removed and a portion of the interior in section.

Like letters refer to the same parts in all of the figures.

The nature of my invention consists in constructing a governor for steam-engines, so that the action of the governor will be direct upon the throttle-valve without the intervention of a balanced bar or lever; in controlling the movement of the governor by pumps working in oil, or other fluid; and in the several new and improved parts and combinations hereinafter set forth and claimed as my invention.

To enable others skilled in the art to make and use my invention, I will proceed to describe its construction and operation.

The outer casing or chest, A, is made of iron, brass, or other suitable metal, and in size will vary to suit different-sized engines, the size shown being suitable for a five-horse-power engine. The same proportion will also be observed in constructing the other parts, with the exception of the weight or ball F, which, for a five-horse-power engine, should weigh about ten pounds, and for a forty-horse-power about twenty-five pounds. I usually make the case or chest tight at all of its joints, but it is not necessary to make it so at the top, except for marine engines.

Into this case or shell I insert, from the top, a tube or cylinder, D, leaving it to project above, as shown, and descending nearly or quite to the bottom, B.

Into this tube I insert a shaft, E, which is fitted to the tube or cylinder D. This shaft is turned off so as to play smoothly in the cylinder, and at J is turned or cut somewhat smaller, so as to leave a space for any oil that may pass the head E' of the shaft, and if any considerable quantity should accumulate, it will pass out at the side holes d or l, and not work out at the top of the cylinder.

On the top of this shaft E, the weight or ball F is placed; and below this I insert into the shaft, or otherwise attach, a short arm, G, in such position that it will form a rest for the weighted shaft with the top of the tube D, or rest upon such tube when the shaft is at its lowest point. This arm G projects out beyond the case A sufficiently far to clear it; and at its outer end is attached the valve-rod H, which passes through it and down through the packed guide or opening I into the steam-pipe G, and is attached directly to the throttle-valve. In some constructions it will pass outside of the steam-pipe, and be attached to a handle or crank of the throttle-valve, as it can be applied as well that way as in the manner shown, but in either case it is attached without the intervention of a balanced bar or forked lever. If, however, from its position, or from the construction of the engine, it should be desirable to use such balanced bar or lever, it can be used, but it will scarcely ever be found necessary or desirable. The rod H is adjusted to the valve by means of the nuts f and g.

The tube or cylinder E is cast with or otherwise attached to the plate or box K, as shown. This plate K rests upon the valves V and cushion L, and the cushion L and plate M, with plate K, form a box, having a cavity, Z, which connects with the cylinder D by means of the opening e.

At each end of this plate, I attach pump-cylinders N and N', N being shown in section at fig. 5. These cylinders are open at both ends in construction, but the lower end is closed by resting upon the seats V of valves W. These valve-seats may be left without permanent attachment, or they may be attached to either plate K or B. They are made hollow, as shown at fig. 2, and are provided at the rim or periphery with inlet-openings, h, and at the top with exit-openings a. The openings a are covered by the valves W, which are

puppet-valves, and are prevented from rising too far by the stem and collar β . The pistons or plungers O are fitted to the pump-cylinders, and are made hollow nearly to the lower ends, for the purposes hereinafter set forth. The cylinders N and N' , fig. 5, connect with the chamber Z by means of the passage or opening j and valves U . The lower end of the valves U is cut away, as shown at fig. 3, so as to leave a partial chamber in their sockets, and are fitted to K only at the swell on their upper ends.

The pistons or plungers O are operated by the bar or walking-beam P , which is supported at the middle by the rod or shaft R , and operated by it. The shaft R passes through the back plate or side of the case or chest A , and is supported by the journal-bearing S . At the outer end of R a lever, T , is attached, the lower end of which is attached by a rod or pitman to an eccentric on the main shaft, or to the valve-rod, so as to give it the same motion as that of the main valve of the engine.

To the outer ends of the beam P , I attach rods or pitmen Q , by hinging them on the bolt R' . These rods pass down into the hollow plungers O , and are pivoted in them at i . By this arrangement, I am enabled to bring the beam P and plungers O close together, and give the beam a rocking motion, and at the same time give the plungers a free vertical movement.

Y , fig. 5, is a tube, screwed into the cylinder D , and, at its outer end, is provided with a stop, X , which can be turned so as to stop off the oil or other fluid entirely or partially, so as to regulate the flow of oil from the cylinder D back into box A , and thereby regulate and control the entire movement of the governor; for if turned off so as to permit a full flow, the oil will pass off as fast as it is pumped into D , and from that point may be turned on so as to stop the entire flow, which will close the throttle-valve. Stopping it at any intermediate point regulates the opening and closing of the throttle-valve to the movement of the engine and the pressure of steam, as it is sensitive and quick in its changes.

I have not shown nor described a throttle-valve, as they are of different forms and locations, and my governor will operate any of them, and operate open stationary engines, or marine engines, as it is not affected by change of position, provided it is not turned too far down. When completed, I fill it with oil up to about the top of the cylinders N .

In operation, the oil or other fluid passes from the box into the valve-case or seat V , through the holes h , and then through the holes a into cylinder N , when the piston O rises. When it descends, the oil passes through the opening j , and lifts the valve U and enters the chamber Z .

The operation of plunger O' , in cylinder N' , repeats the same movement of the oil on that side. From chamber Z the oil is forced through the openings e into cylinder D , which lifts the weighted shaft E , and also rod or pitman H , and with it the throttle-valve. The weight F tends to force the oil out of the cylinder D through the stop or regulating-cock y x ; and the rapidity with which it is forced out depends upon the turn of the cock. To prevent it from rising too high at any time, holes, d , are made in the cylinder D , so that in any event the shaft E cannot be forced above that point. The hole b is simply for the escape of any oil which may have passed up the shaft.

If a rapid motion is communicated by lever T , the action of the pumps is increased, which will hold the shaft E , with the rod H , at a higher level, and close the valve; and as the motion is decreased, the valve opens, so that an even pressure is maintained at all times, and regulated instantly by simply turning the stop x , which regulates the outflow of the oil.

It will also be seen from the operation, that when the rod or pitman, which operates the crank or lever T , is attached to the valve-rod or eccentric, the pumps will act in unison with the cut-off valves, and the throttle-valve being nearer the boiler, the action will be first felt on that, so that, to a great extent, it is made or may be adjusted to make a cut-off valve of the throttle-valve.

It will also be observed that the pump is made of two single pumps, as shown, but it will not change the operation or principle of the machine in this respect to make one double-acting pump to take the place of the two single ones; and it will require only slight changes of construction to make this variation or modification, the condition being that the pump shall, in either case, be double-acting.

This governor will be found a simple and efficient one, accurate and sensitive in its movements, as I have found from trials of the same.

Having thus fully described my invention, what I claim as new, and desire to secure by Letters Patent, is—

The arrangement of the lever or crank T , beam P , and pumps N with the cylinder D , regulating-stop y x , shaft E , rod H , and case A B , substantially as and for the purposes specified.
